UNITED STATES PATENT OFFICE.

ARTHUR KATZINGER, OF CHICAGO, ILLINOIS, ASSIGNOR TO EDWARD KATZINGER COMPANY, OF CHICAGO, ILLINOIS.

PROCESS OF MAKING CONTAINERS.

Application filed July 7, 1924. Serial No. 724,736.

This invention relates to containers made of sheet metal but applies particularly to a process of constructing these containers economically, strongly, and of such form 5 that they will be sanitary.

My invention relates particularly to means for strapping or fastening the containers together in a row or working unit. Such strapping is necessary in handling containers 10 of this type, as for example, in wholesale bakeries where containers are used for baking bread; the labor involved in handling a single container would be prohibitive, whereas, if containers are strapped together 15 in units of from three to eight, the labor of handling these containers in the bakery is proportionately reduced and entirely satisfactory results in other respects are secured. I do not of course wish to limit my invention 20 to any particular number of containers, as obviously the process which I have devised may be applied irrespective of the number of containers involved.

The object of this invention is to provide 25 a simple, efficient, economical process of manufacturing containers of this type in quantity.

Containers strapped together in accordance 30 with my process will be extremely strong, durable and rigid. By applying my method in strapping containers, I have found that the assembled unit will hold together so tenaciously that the life of the combination is practically equal to the life of any 35 of the single units. This has not been the case in containers strapped together by previous methods, as invariably the strapping or fastenings will loosen, which eventually destroys the usefulness of the entire group.

40 Other objects of this invention will be apparent from the description and claims which follow and from the attached drawing.

Referring to the drawing, Figure I shows 45 a set of finished containers strapped together in accordance with the process which I have invented. Figure II shows a single unit before assembling by my process. Figure III shows a portion of a container placed 50 in a press prior to assembling, while Figure IV shows the same portion of a container after forcing the rivet into position but before heading over the rivet.

55 Referring to Figure I, (1) indicates the unit container, which is normally made in

the form of a rectangular box open at the top, with inclined sides and ends. As shown in Figures I and II, I have found it helpful to fold up the narrow ends (2) and bend them back so that they form overlapping 60 portions (3). I have also found it expedient to roll over the upper edges (4) of said containers around a wire (5), or other stiffening means. The group of containers are held together by the straps (6 65 and 7) which unite them firmly and durably into a single working unit.

In the finished group the strap (7) is attached to the individual containers by rivets (8, 9, 10, 11, etc.), the rivets being 70 forced only through the overlapping portion (3) of the ends of the containers, and of course through the strap (7).

It will be apparent that such a construction gives a finished group of containers 75 in which the interior surface of the container is smooth and free from all holes, edges and rough spots of any nature. This construction is particularly in contrast to a much inferior construction in which the rivets pass entirely through the ends of the container. A construction of the latter type naturally produces a container whose interior wall has at least four round rivet 80 heads which create unsightly lumps or spots 85 on the material later placed in the container, and at the same time provide crevices in which dirt may lodge and bacteria collect, thus giving an unsanitary condition 90 as well as making the container difficult 95 to clean and producing marks upon the articles which are placed in the container, such as loaves of bread, in case the container is used in a bakery.

The method of constructing containers 95 which I have invented, consists in first forming the individual container into the general shape shown in Figure II. I then insert a rivet or fastening member (12 and 13) under the end folds as shown in Figure 100 II, having first slightly lifted or bent the end folds to permit such insertion. The container is then placed in a press, as shown in Figure III, the strapping member (7) placed in position above the end folds (3) 105 and over the rivet member (12). The press is then operated, press member (14) traveling toward press member (15), which forces rivet (12) first through fold member (3) 110 and then through strap (7), the assembled

combination eventually assuming the condition shown in Figure IV, in which the rivet is smoothly and tightly forced through both the end fold and the strap member. The rivet is then headed over to prevent withdrawal or loosening, and the construction assumes the shape indicated in Figure I.

While I do not wish to be limited to any special construction or materials, I have found that sheet iron covered with tin, or what is commonly called tinplate, forms a very desirable material from which to construct the containers. For the strapping member I have found that steel or iron straps, either plain or galvanized, give excellent service and are very satisfactory. The rivets may be formed either from copper or soft iron, as desired. I do not wish to be restricted to the exact materials described above, and am merely mentioning them to give clearness and definiteness to this disclosure of my invention.

It will be apparent from the description of the process as given above, that containers strapped together as I have described are exceptionally rigid and the fastening will be exceptionally durable. By forcing the rivet to create its own hole an unusually tight fit is secured, which gives a strength to the finished article limited only by the strength of the materials used. There will obviously be no looseness, lost motion, or other means for rattle or relative movement between the various parts thus fastened. It will also be apparent that the process which I have invented is very economical in carrying out, for the reason that no previous punching of holes is required. The objection to previous punching of holes for the assembling of these units, lies not only in the labor involved in such an operation, but results also from the difficulty which always exists in making the holes punched in the ends of the containers coincide with the holes punched in the strap. It will be readily apparent that if the holes punched in the end of the container are made before bending, very slight differences in the degree of bending will cause serious difficulties in making the holes in the strap coincide with the holes in the container. If it is attempted to overcome this difficulty by making the rivet a

loose fit in the hole, obviously opportunity is immediately introduced to encourage relative motion between the strapping and the container. The above difficulties are of course entirely removed by the method which I have invented, and a stronger, more durable container results.

It is also possible to successfully use a rivet having a smaller head, in the construction which I have invented, as where any appreciable amount of clearance is permitted between the size of the hole in the end of the container and the diameter of the rivet, the difficulty may always arise that the rivet head will be pulled through the hole in the end of the container. Obviously, where the rivet forces its way through the end of the container, creating its own hole, the maximum degree of tightness is obtained.

It will be apparent that many variations may be made in the actual carrying out of the process and still come within the scope of my invention. For example, if desired, I may force the rivet first through the ends of the container and then through the strap, or I may force the rivet through both pieces in a single operation. These modifications are optional, and I regard them as coming within the scope of my invention.

Having now described my invention, what I claim as new and wish to secure by Letters Patent is as follows:

1. An article of manufacture consisting of a series of containers formed from sheet metal folded at the corners to form a pan, a strap extending along the ends of said containers and serving to unite them into a single unit, rivets passing through the folded end of said pans and said straps, the joint between said rivets and the edges of the coacting hole in said ends of said pans, and the edges of the coacting hole in said strap being such as to insure absolutely tight contact at all points with said rivet.

2. An article of manufacture consisting of a multiple of containers fastened together by a strap riveted to the folds of the ends of said containers the rivets and the edges of the holes through which the rivets pass being arranged to make absolutely tight contact at all points.

ARTHUR KATZINGER.
